CLAIM

The ornamental design for an animal feeding apparatus, as shown and described.

DESCRIPTION

FIG. 1 is a front perspective view of an animal feeding apparatus according to a first embodiment of the new design; FIG. 2 is a front view thereof; FIG. 3 is a rear view thereof; FIG. 4 is a left side view thereof; FIG. 5 is a right side view thereof; FIG. 6 is a top view thereof; FIG. 7 is a bottom view thereof;

FIG. 8 is a front perspective view of an animal feeding apparatus according to a second embodiment of the new design;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a front perspective view of an animal feeding apparatus according to a third embodiment of the new design;

FIG. 16 is a front view thereof;

FIG. 17 is a rear view thereof;

FIG. 18 is a left side view thereof;

FIG. 19 is a right side view thereof;

FIG. 20 is a top view thereof;

FIG. 21 is a bottom view thereof;

FIG. 22 is a front perspective view of an animal feeding apparatus according to a fourth embodiment of the new design;

FIG. 23 is a front view thereof;

FIG. 24 is a rear view thereof;

FIG. 25 is a left side view thereof;

FIG. 26 is a right side view thereof;

FIG. 27 is a top view thereof; and,

FIG. 28 is a bottom view thereof.

The broken lines illustrating portions of the animal feeding apparatus form no part of the claimed design. The dot-dash broken lines define the bounds of the claimed design and form no part thereof.
